(57) **CLAIM**

We claim the ornamental design for a packaging container, as shown.

DESCRIPTION

FIG. 1 is a perspective view of an opened packaging container of the claimed design.

FIG. 2 is a perspective view of a closed packaging container of the claimed design.

FIG. 3 is a right side view of a closed packaging container of the claimed design.

FIG. 4 is a left side view of a closed packaging container of the claimed design.

FIG. 5 is a back side view of a closed packaging container of the claimed design.

FIG. 6 is a front side view of a closed packaging container of the claimed design.

FIG. 7 is a plan view of the bottom of a closed packaging container of the claimed design.

FIG. 8 is a plan view of the top of a closed packaging container of the claimed design.

FIG. 9 is another plan view of the bottom of a closed packaging container of the claimed design; and,

FIG. 10 is another plan view of the top of a closed packaging container of the claimed design.
